(57) **CLAIM**

The ornamental design for a sterilization container, as shown and described.

DESCRIPTION

FIG. 1 is a perspective view of a new design showing a sterilization container according to the present invention; FIG. 2 is a top view of the sterilization container of FIG. 1; FIG. 3 is a front view of the sterilization container of FIG. 1;

FIG. 4 is a rear view of the sterilization container of FIG. 1; FIG. 5 is a bottom view of the sterilization container of FIG. 1;

FIG. 6 is a left side view of the sterilization container of FIG. 1;

FIG. 7 is a right side view of the sterilization container of FIG. 1;

FIG. 8 is another perspective view of the sterilization container of FIG. 1, but showing the sterilization container in a different configuration with a tray portion of the sterilization container removed from a body portion of the sterilization container;

FIG. 9 is a top view of the sterilization container of FIG. 8; FIG. 10 is a bottom view of the sterilization container of FIG. 8;

FIG. 11 is a left side view of the sterilization container of FIG. 8; and,

FIG. 12 is a right side view of the sterilization container of FIG. 8.

The broken lines illustrate portions of the sterilization container that do not form part of the claimed design.

1 Claim, 8 Drawing Sheets
